SANITARY DEVICE

Carl W. Peters, Caledonia, Wis.

Application May 26, 1939, Serial No. 275,827

4 Claims. (Cl. 4—1)

This invention relates to sanitary devices, and more particularly to a novel sanitary device of the type adapted to handle toilet paper by mechanical means.

5 An object of the invention is to provide a device of the type which will permit a choice in the number of sheets of tissue to be used in one application.

Another object of the invention is to provide a 10 simple device which may be attached to a conventional closet seat without altering or remodeling the latter.

Other and further objects of the invention will 15 appear as the description proceeds, reference being had to the accompanying drawing, in which:

Fig. 1 is a top plan elevational view of a toilet seat showing a sanitary device attached thereto embodying the invention.

Fig. 2 is a vertical cross-sectional view taken 20 through the tissue container and the adjacent side of the toilet seat.

Fig. 3 is a view partly in elevation and partly in section of the applicator rod and the seat.

Fig. 4 is a view partly in section and partly in 25 elevation showing the tissue container and baffle plate.

Referring more particularly to the drawing, the numeral 10 refers to the device generally, which includes a rectangular base bracket 11, 30 subjoined to the toilet seat 12, by the screws 13 through the spacer 14. The base bracket or plate 11 is apertured at 15. Underlying the aperture at 15 is the container bracket 16, which is likewise apertured at 17 to register with the aperture 35 in plate 11. Bolts 18 secure the bracket 16 to the plate 11 in spaced relation in order that the applicator arm 19 may move therebetween and will be journaled with a sliding fit by its ball joint 20 in the apertures forming upper and 40 lower socket formations at 15 and 17.

A handle 21 is formed at the outer end of applicator arm 19, which has fixed on its inner end, an applicator 22 formed of rubber or other resilient material, and tapered reducedly from its 45 fixed to its free end. The applicator is attached by its larger end, to the inner end of the applicator arm 19, and extends radially thereof.

A container for sheet tissue, 23, is attached by 50 means of angle brackets 24 and threaded or other means 25, under the bracket 16. The container 23 is a rectangular box extending longitudinally substantially radially of the toilet seat.

A cover 26 is normally held in place by the clip 55 end portion 27. Extending curvedly upwardly and inwardly of the bracket 16 and fixed thereto

is a retainer strip 28 which terminates under the outer and lower edge of the toilet seat 12.

A false bottom 29 is pressed upwardly by coil expansion springs 30, preferably four in number and situated adjacent the corners of the bottom 5 29.

In use, the handle 21 is grasped and the rod 19 rotated on a horizontal plane to bring the applicator 22 under the baffle 28 and over the open end of the container 23. The rotation in 10 a clockwise direction of handle 21 and at the same time manipulating the same to press the applicator 22 downwardly against the topmost sheet of the tissue paper 31 will result in the picking up of a sheet or sheets of the tissue 31 by said 15 applicator, according to the amount of pressure exerted by the user. The applicator is rotated to bring the paper upwardly thereof and it may be then carried on the applicator to a position centrally of the seat 12. The applicator 22 may 20 be rotated backwardly and forwardly at this point for the desired purpose; after which a rotation downwardly of the applicator will discard the used paper into the toilet bowl. It will be apparent that the applicator, being formed of a 25 resilient or rubber material, will, when rubbed with the proper degree of pressure, tend to dislodge one or more sheets of tissue as it is turned or moved thereagainst, by the friction thereof.

Having thus described the invention, it will be 30 understood that the device is capable of various modifications in structure and design, without departing from the spirit thereof, within the scope of the appended claims.

I claim:

1. The combination with a water-closet of 35 means for retaining sheet tissue, an arced baffle plate associated therewith, a closet seat, a manually operable rod swiveled under said seat, a rubber applicator radially disposed on an end of the 40 rod for frictionally appropriating the sheets of tissue by rotation of said applicator under the baffle and against the sheets and carrying said sheets interiorly of the closet seat area for the purpose specified.

2. In a device of the class described, a rod attached under a conventional toilet seat, and a member thereon of resilient material adapted by rotation to frictionally appropriate sheets of tissue from a container, the said rod mounted to 50 pivot horizontally and also to rotate on its axis.

3. In combination with a conventional toilet seat, a bracket subjoined thereto having a ball socket therein, a rod having a ball bearing integral therewith intermediate the ends and en- 55

gaged in said socket, a container held adjacent the seat, a spring-pressed bottom therein, a plurality of sheets of tissue paper in said container, a resilient member mounted on an end of said rod 5 adapted when rotated to frictionally remove tissue from the container.

4. In a device of the class described, a closet seat, a container for sheet tissue connected therewith, a rod swivelly attached under said seat ro-

tatable on its axis and swingable in a horizontal arc, a rubber member mounted on an end of said rod, a curved retainer plate disposed over said container whereby when the rubber member is rotated to dislodge a sheet of tissue said plate 5 will retain the tissue on the rubber member preparatory to the movement thereof into the area of the closet seat.

CARL W. PETERS.
